UNITED STATES PATENT OFFICE

2,158,602

ELECTRICAL HEATING APPARATUS

Ernest N. Calhoun, Pittsburgh, Pa., assignor, by
mesne assignments, to Edwin L. Wiegand, Pitts-
burgh, Pa.

Application April 13, 1937, Serial No. 136,587

22 Claims.

(Cl. 219—39)

My invention relates to electrical heating apparatus, and more particularly to such apparatus of the forced convection or circulation type, and the principal object of my invention is to provide new and improved electrical heating apparatus of these types.

In the drawing accompanying this specification, and forming part of this application, I have shown, for purposes of illustration, several forms 10 which my invention may assume. In this drawing:

Figure 1 is a plan view of a unitary cell embodying my invention,

Figure 2 is a section taken along the line 2—2 15 of Figure 1,

Figure 3 is a fragmentary view, in longitudinal section, of heating apparatus embodying my invention, and shows one way in which cells such as shown in Figures 1 and 2 may be utilized,

Figure 4 is a view, partly fragmentary, in longitudinal section, showing heating apparatus embodying my invention and illustrating another way in which the unit cells shown in Figures 1 20 and 2 may be utilized,

Figure 5 is a fragmentary sectional view taken along the line 5—5 of Figure 2, and

Figure 6 is a section, partly fragmentary, taken along the line 6—6 of Figure 5.

Referring first to the unitary cell of Figures 1 30 and 2, the cell here illustrated comprises an electrical heating unit 10 here shown as disposed between spaced wall members 11, 12. The electrical heating unit comprises a general body portion 13 and heat dissipating means 14 provided thereon, the heat dissipating means 14 extending transversely between the wall members 11, 12.

The general body portion 13 of the heating unit is here shown as of oblong cross-sectional outline. The primary body portion is in the form 40 of an electric heater 15 of the strip type, but not of rectilinear form, and is here shown as including a sheath comprising a sheet metal channel having a bottom wall 16 and side flanges 17, 18 along with a longitudinally extending strip of 45 sheet metal 19 closing the open side of the channel, the free ends 20 of the flanges 17, 18 being bent against the outside of the closure strip 19.

Disposed within the sheet metal sheath of the strip heater 15 is a resistor 21 which is here 50 shown as a strip of electrical resistance material, the strip being of undulating form and extending longitudinally within the sheath one or more times as may be desired. It will be understood that the resistor 21 may be of any other suitable form. The resistor 21 is insulated from the

sheath by insulation 22 disposed within the sheath and in which the resistor is embedded. The insulation 22 is desirably refractory and in particular highly compacted granular refractory material, which, while electrically insulating, is 5 heat conducting.

The heat dissipating means 14 here shown comprises fin means. The fin means may be of any suitable form. In the illustrated embodiment the fin means includes a plurality of fin elements 23 spaced longitudinally of the general body portion 13 and extending transversely thereof. Each fin element 23 is, in this instance, integral with one end of an annular collar 24 which is of such form and dimensions as to fit 15 snugly but slidably over the sheath of the strip heater 15. The end of each collar 24 at which the fin element 23 is provided has an opening which has a recess or outward flare 25, and the end 26 of the adjacent collar 24 is adapted to 20 wedge into the recess or flare 25. If desired the end 26 may be slightly beveled to promote entrance of the end 26 into the recess or flare 25.

The fin elements 23 are here shown as of oblong rectangular outline.

One end of the strip heater 15 is here shown as provided with a pair of terminals 27, 28, one of which, 27, is shown in side elevation in Figure 1 and the other of which, 28, is directly behind the terminal 27. The terminals 27, 28 are connected 30 within the sheath to the resistor 21.

In making such a heating unit 10 as shown in Figure 1 the primary body portion, constituted by the strip type heater 15, may be first completed in the form of a rectilinear strip heater, 35 this strip heater being entirely complete and comprising all of the constructional features hereinbefore pointed out with respect to the strip type heater 15, with the exception that the body portion is rectilinear. The finned elements constituted by the collars 24 and fin elements 23 may be then telescoped over the strip heater, and, desirably, enough finned elements are telescoped onto the strip heater so that substantially the entire length of the heater is occupied by finned 40 elements. The last, or both the first and last finned element telescoped onto the heater may, if desired, be brazed to the sheath of the heater, or otherwise suitably fastened thereto. At this stage of the process the heating unit comprises a 45 strip heater provided with heat dissipating means, and the general locus of the heating unit, as determined by the strip heater, is rectilinear. The heating unit is then bent to the form shown in Figure 1 in which, as shown, the unit 10 forms 50 55

a complete circle. The adjacent ends of the strip heater 15 are desirably joined by a weld 29 or otherwise suitably fastened to each other so that the strip heater forms a continuous loop, in this instance circular.

The finned strip heater may be brought to the form shown in Figure 1, manually, by holding the finned strip heater at its ends and bending it around some round object, with its wider side 10 against the round object. Another way is to place the finned strip heater between templates or jigs and press it into shape. Pads may be used on the templates in the form of a rubber coating, for example, to keep the fins from skidding and being 15 bent out of proper spacing. Still another way is to pass the finned strip through bending rolls which may be covered with a padding such as rubber. On the other hand, the unit may also be produced by first bending a strip heater to the 20 desired form and then applying the fin means thereto.

The outer wall member, 12, is here shown as formed by the bottom of a channel shaped member 34 having outwardly directed flanges 30, 31, 25 and in like manner the inner wall member, 11, is here shown as formed by the bottom of a channel shaped member 35 having radially inwardly directed flanges 32, 33. Both of the channel shaped members are here shown as of an 30 annular form, the radially inside surface of the wall 12 being of such diameter as desirably to fit snugly but slidably over the locus defined by the radially outer margins of the fin elements 23. In like manner the radially outside surface of the 35 wall 11 is of such diameter as to fit snugly but slidably over the locus defined by the radially inner margins of the fin elements 23. The width of the walls 11, 12 is here shown as approximately the same, but more specifically, somewhat longer than the wider margin of the fin elements 23. The channel shaped members 34, 35 may be 40 formed by casting, each member to form an integral ring of channel shaped cross-section, or these members may be fabricated. If the members are cast, a desirable metal is aluminum, but other metals may be utilized.

When the heating unit 10 has been assembled with the two channel or ring members 34, 35, the heating unit and the ring members may be 50 fastened together as by tack brazing, as shown at the points 36, or otherwise suitably fastened together, as desired. In so tack brazing, or otherwise fastening the parts together, it is not necessary to tack braze every fin element 23 to the 55 adjacent ring member 34, 35, but if desired only a small number of fin elements 23 may be so tack brazed, say at diametrically opposite points of the unit cell.

The outer ring member 34 is here shown as 60 carrying a pair of insulated line terminals 37, 38 one of these terminals, 37, being connected by a conductor 39 to the terminal 27 of the heating unit 10, and the other terminal, 38, being connected by a conductor 40, directly behind the conductor 39 in Figure 1, to the other terminal, 28, of the heating unit 10. Conductors leading to a source of current may be of course connected to the line terminals 37, 38, to supply the resistor 21 with current.

The flanges 30, 32, and 31, 33, serve to readily 70 connect a unit cell, such as shown in Figures 1 and 2, either with conduit means not containing a heating unit or with another unit cell such as shown in Figures 1 and 2. The flanges 32, 33 75 of the inner ring member, 35, are here shown as

provided with a suitable number of holes, here shown as four holes 41, and the flanges 30, 31 of the outer ring member, 34, are here shown as also provided with a suitable number of holes, radially aligned with the holes 41, here shown as 5 four holes 42. The holes 41, 42 in the flanges 31, 33, for example, may be placed in registry with the similar holes in the flanges 30, 32 of an adjacent cell, and the cells fastened together by bolts and nuts 51 cooperating with the registering 10 holes, as indicated in Figure 3.

In Figure 3, three unit cells A, B, C, each such as shown in Figures 1 and 2, are shown assembled, but it is to be understood that a unit cell may be used singly or in association with any 15 desired number of other cells. The three cells A, B, C shown in Figure 3 are here shown as further tied together by tie rods 43, these tie rods passing through registering holes 44 in the flanges 30, 31 of the outer ring member, 34. 20

In Figure 3 the cell A is shown as having connected thereto a conduit 45, the conduit being provided with a flange 46 having holes registering with the holes 42, 44 in the flange 30 of the outer ring member, 34, and fastened to that flange by 25 bolts and nuts (not visible) and also by the tie rods 43. The conduit 45 may be of any suitable form and extends to a source of fluid under pressure (not shown). Here shown as fastened to the flange 32 of the ring member 35 of unit A 30 is a disc or baffle 47 having holes registering with the holes 41 in the flange 32 and fastened to the flange by nuts and bolts 48 cooperating with the registering holes. The baffle 47 is desirably utilized to cause air or other fluid supplied by the 35 conduit 45 to flow, as indicated generally by the arrows in Figure 3, through the annular passage provided by the outer and inner ring members, 34, 35 of the cells A, B, C, thus causing the fluid to abstract heat from the heat dissipating means of 40 these unit cells.

The fluid issuing from the last unit cell, C, may be allowed to freely escape therefrom, depending upon the manner in which it is desired to use the heating apparatus, or the heated fluid 45 may enter another conduit means 49 having a flange 50 cooperable with the flange 31 of the outer ring member 34 of the last unit cell, C. The conduit 49 may be of any suitable form and may be led to the point where it is desired to utilize 50 the heated fluid.

In Figure 4 is shown another way in which one or more unit cells may be utilized. In this form of heating apparatus any desired number of cells, here shown as three in number D, E, F, are bolted together in the manner already explained in connection with the unit cells A, B, C, of Figure 3. As here shown a fan 52 is driven by a motor 53, the fan 52 operating within an annular wall 54 bolted to the end unit D. A baffle 55, similar to the baffle 47, is also provided. The cells D, E, F, are here shown as surrounded by a jacket or conduit means 56 having an inlet opening 57; and the left hand end of the conduit means is here shown as also serving as a 60 housing 58 to lead air to the inlet side of the fan 52. In the embodiment of Figure 4 the fluid accordingly enters into the inlet 57 and is pre-heated by heat dissipated from the outside of the outer ring members, 34, of the units D, E, 70 F, then proceeds to the left side of the fan 52, and is then forced by the fan through the annular passage provided by the cells, similarly to Figure 3.

From the foregoing it will be apparent to 75

those skilled in the art that each of the illustrated embodiments of my invention provides a new and improved electrical heating apparatus, readily and conveniently constructed and assembled, and accordingly, each accomplishes the principal object of my invention. On the other hand, it also will be obvious to those skilled in the art that the illustrated embodiments of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. Electrical heating apparatus, comprising: an electrical heating element; a wall spaced from 20 and disposed alongside of said heating element, said wall being provided by the bottom portion of a channel shaped element the flanges of which are directed away from said heating element; and heat dissipating means for dissipating heat 25 from said heating element, said heat dissipating means being fastened to said wall.

2. Electrical heating apparatus, comprising: an electrical heating element the longitudinal locus of which is arcuate; an arcuate wall spaced 30 from said heating element and concentric therewith, said wall being provided by the bottom portion of a channel shaped element the flanges of which are directed away from said heating element; and heat dissipating means for dissipating heat 35 from said heating element, said heat dissipating means being fastened to said wall.

3. Electrical heating apparatus, comprising: an electrical heating element having a body portion having an oblong cross-sectional outline; a wall spaced from said heating element and facing 40 a wider side of said body portion, said wall being provided by the bottom portion of a channel shaped element the flanges of which are directed away from said heating element; and heat dissipating means for dissipating heat from said heating element, said heat dissipating means being fastened to said wall.

4. Electrical heating apparatus, comprising: conduit means so constructed and arranged that 50 it forms a passage annular in cross-section providing a path for the flow of fluid from one end of said conduit means to the other; a heating element disposed in said annular passage and in said path; said conduit means and said heating 55 element being so constructed and arranged that they form a unitary structure; said conduit means being so constructed and arranged that it may be held to another conduit means forming a continuation of at least the outer wall of 60 said first named conduit means.

5. An electrical heating unit, comprising: a resistor; metallic sheath means within which said resistor is disposed; means for insulating 65 said resistor from said sheath means; said sheath means forming a loop having ends, said ends being in abutment with each other; and means permanently fastening said abutting ends to each other.

6. An electrical heating unit, comprising: a 70 resistor; metallic sheath means within which said resistor is disposed; means for insulating said resistor from said sheath means; said sheath means forming a loop having ends, said ends being in abutment with each other; means permanently fastening said abutting ends to each 75

other; and heat dissipating means mounted on said sheath and comprising longitudinally spaced fin means extending transversely of said sheath.

7. Electrical heating apparatus, comprising: an electrical heating unit including an elongated 5 heating element and heat dissipating means mounted on and unitary with said heating element; a wall spaced from said heating element and contacting said heat dissipating means; said heat dissipating means comprising fin means 10 spaced longitudinally of said heating element and extending transversely of the space between said element and said wall; and means permanently fastening to said wall at least some of the otherwise free ends of said fin means contacting 15 said wall.

8. Electrical heating apparatus, comprising: a plurality of electrical heating units, each unit comprising an electrical heating element and wall means constructed and arranged to leave a 20 space between said element and said wall means thereby to guide fluid through said space and into heat dissipating relation with said element; and means holding an end of the wall means of one unit in approximate abutment with an end 25 of the wall means of an adjacent unit, said holding means and said wall means being so constructed and arranged that said respective wall means jointly form a composite substantially continuous wall means and that said spaces form 30 continuations of each other to form a continuous passage so that fluid may flow continuously through one space into and through the adjacent space.

9. Electrical heating apparatus, comprising: 35 conduit means including a plurality of sectional units; each of said sectional units having disposed therein and unitary therewith at least one electrical heating element; heat dissipating means mounted on and unitary with each heat 40 element; said heat dissipating means including fin means extending transversely of the respective heating element and longitudinally of said conduit means; and means fastening together adjacent ones of said sectional units so that said sectional units form said conduit means providing a continuous passage through which fluid 45 may be passed and into contact with said heating elements.

10. Electrical heating apparatus, comprising: 50 an electrical heating unit having a body the general longitudinal locus of which is substantially circular; heat dissipating means on said body, including a plurality of annular members disposed axially adjacent each other about said body, said annular members being respectively provided with a transversely extending flange, the ends of said flanges defining a circle; a cylindrical wall surrounding and contacting said heat dissipating means; and means permanently fastening to the inner periphery of said wall at least 55 some of the ends of said flanges contacting said wall.

11. Electrical heating apparatus, comprising: 65 an electrical heating unit including an elongated heating element and heat dissipating means mounted on and unitary with said heating element; a wall spaced from said heating element and contacting said heat dissipating means; said wall being provided by the bottom portion of a 70 channel shaped element the flanges of which are directed away from said heating unit; said heat dissipating means comprising fin means spaced longitudinally of said heating element and extending transversely of the space between said 75

element and said wall; and means permanently fastening to said wall at least some of the ends of said fin means contacting said wall.

12. Electrical heating apparatus, comprising: an electrical heating unit including an elongated heating element the longitudinal locus of which is arcuate and heat dissipating means mounted on and unitary with said heating element; an arcuate wall spaced from and concentric with said heating element and contacting said heat dissipating means; said wall being provided by the bottom portion of a channel shaped element the flanges of which are directed away from said heating unit; said heat dissipating means comprising fin means spaced longitudinally of said heating element and extending transversely of the space between said element and said wall; and means permanently fastening to said wall at least some of the ends of said fin means contacting said wall.

13. Electrical heating apparatus, comprising: an electrical heating unit including an elongated heating element and heat dissipating means mounted on and unitary with said heating element; said heating unit having a body portion having an oblong cross-sectional outline; a wall spaced from said heating element and facing a wider side of said body portion and contacting said heat dissipating means; said wall being provided by the bottom of a channel shaped element the flanges of which are directed away from said heating element; said heat dissipating means comprising fin means spaced longitudinally of said heating element and extending transversely of the space between said element and said wall; and means permanently fastening to said wall at least some of the ends of said fin means contacting said wall.

14. Electrical heating apparatus, comprising: a plurality of electrical heating units, each unit comprising an electrical heating element and wall means constructed and arranged to guide fluid into heat dissipating relation with said element; said respective wall means being so constructed and arranged that said respective wall means are adapted jointly to form a composite substantially continuous wall means; and means holding said respective wall means so as jointly to form a composite substantially continuous wall means, said holding means being so constructed and arranged that it is attachable to and detachable from said wall means.

15. Electrical heating apparatus, comprising: conduit means so constructed and arranged that it forms a passage annular in cross-section providing a path for the flow of fluid from one end of said conduit means to the other; a heating element disposed in said annular passage and in said path; said conduit means and said heating element being so constructed and arranged that they form a unitary structure; said conduit means having flange means unitary with the outermost wall of said conduit means and extending outwardly at the respective ends of said wall, said flange means being constructed and arranged for connection to flange means on another conduit means.

16. Electrical heating apparatus, comprising: conduit means including a plurality of sectional units, at least two adjacent units being of substantially uniform cross-sectional outline and disposed with their adjacent open ends co-axial; each of said sectional units having disposed therein and unitary therewith at least one electrical heating element; and means fastening together

adjacent ones of said sectional units so that said sectional units form said conduit means providing a continuous passage through which fluid may be passed and into contact with said heating elements.

17. Electrical heating apparatus, comprising: conduit means including a plurality of sectional units, at least two adjacent units being of substantially uniform cross-section outline and disposed with their adjacent open ends co-axial; transversely extending flanges on said units; each of said sectional units having disposed therein and unitary therewith at least one electrical heating element; and means fastening together adjacent ones of said flanges on adjacent units so that said sectional units form said conduit means providing a continuous passage through which fluid may be passed and into contact with said heating elements.

18. Electrical heating apparatus, comprising: conduit means including a plurality of sectional units, at least two of said units being of substantially uniform cross-sectional outline and disposed with their adjacent open ends co-axial; each of said sectional units having disposed therein and unitary therewith at least one electrical heating element; heat dissipating means mounted on and unitary with each heating element; said heat dissipating means including fin means extending transversely of the respective heating element and longitudinally of said conduit means; and means fastening together adjacent ones of said sectional units so that said sectional units form said conduit means providing a continuous passage through which fluid may be passed and into contact with said heating elements.

19. Electrical heating apparatus, comprising: conduit means constructed and arranged to provide a path for fluid flowing therethrough; an elongated electrical heating element having a body portion disposed within said conduit means transversely of the path provided for fluid flow and spaced from a wall of said conduit means; heat dissipating means mounted on and unitary with said heating element, said heat dissipating means comprising transverse fin means spaced longitudinally of said heating element and extending transversely across said space from said body portion to said wall; and means permanently fastening to said wall at least some of the ends of said fin means contacting said wall.

20. Electrical heating apparatus, comprising: conduit means including a plurality of sectional units constructed and arranged to provide a path for fluid flow; each of said sectional units having wall surfaces serving to guide fluid flowing through the respective sections, and each of said sectional units having disposed therein and unitary therewith at least one electrical heating element in the path provided for fluid flow; transverse flanges on adjacent units at the adjacent ends of said wall surfaces of adjacent units; and means fastening together adjacent ones of said flanges on adjacent units so that said wall surfaces provide a continuous passage through which fluid may be passed and guided by said wall surfaces into contact with said heating elements.

21. Electrical heating apparatus, comprising: a tube section for use in series with another tube section to form a sectionalized tube providing a path for fluid flowing therethrough in the direction of the longitudinal axis of the sectionalized tube; an electrical heating element disposed within said tube section in the path provided for

fluid flow; said tube section and said heating element being so constructed and arranged that they form a unitary structure; said tube section terminating at its opposite longitudinal axial ends so as to provide end openings the planes of which are respectively transverse to the longitudinal axis of said tube section; and said tube section at said ends being so constructed and arranged that it may be fastened in longitudinal endwise abutment to another tube section having a cooperating open end of matching cross-sectional outline and forming a continuation of said first named tube section.

22. Electrical heating apparatus, comprising: a sectionalized tube providing a path for fluid flow therethrough in the direction of the longitudinal axis of said sectionalized tube; said sectionalized tube including a plurality of tube sec-

tions, each providing a section of said path, each tube section terminating at its opposite longitudinal axial ends so as to provide an entrance opening and a discharge opening; the planes of which end openings are respectively transverse to the longitudinal axis of the tube section at the respective said ends of the tube section, adjacent tube sections having their discharge and entrance ends of matching cross-sectional outline and in cooperating longitudinal endwise abutment; each tube section having disposed therein an electrical heating element in the path provided for fluid flow; each tube section and respective heating element disposed therein being so constructed and arranged as to form an individual unitary structure; and means for fastening together adjacent abutting ones of said tube sections.

ERNEST N. CALHOUN.
